Francis G. Merser, Framingham, Mass., assignor to Dennison Manufacturing Company, Framingham, Mass., a corporation of Nevada

Filed Nov. 21, 1967, Ser. No. 9,494

Term of patent 14 years

Int. Cl. D8—99

U.S. Cl. D96—1

Fig. 1

Fig. 2

Fig. 3

FIG. 1 is a top plan view of a filament for attaching a tag to an article, showing my new design;

FIG. 2 is a side elevational view; and

FIG. 3 is an enlarged bottom plan view thereof.

The broken-line representation of a tag in FIGS. 1 and 2 is for the purpose of illustration only, it being understood that a portion of the filament is broken away in FIGS. 1 and 3.

I claim:

The ornamental design for a filament for attaching a tag to an article, as shown and described.
